UNITED STATES PATENT OFFICE.

FRANK W. MORSE, OF SAN FERNANDO, CALIFORNIA.

AUTOMOBILE-CURTAIN WINDOW.

1,356,389.

Specification of Letters Patent. Patented Oct. 19, 1920.

Application filed November 5, 1919. Serial No. 335,898.

To all whom it may concern:

Be it known that I, FRANK W. MORSE, a citizen of the United States, residing at San Fernando, in the county of Los Angeles and State of California, have invented certain new and useful Improvements in Automobile-Curtain Windows, of which the following is a specification.

My invention has special reference to automobile curtains usually provided with celluloid or other transparent, but flexible portions, constituting the windows, and my said invention primarily has for its purpose to provide a flexible curtain window frame 10 of the general character mentioned of a simple, economical and substantially rigid construction and which is especially designed for supporting a window glass securely within the inner edges of the frame.

Another object of my invention is to provide a curtain window frame that may be quickly and effectively installed without the need of skilled labor and which when applied, provides a clear vision for the driver.

A still further object of my invention is to provide a window curtain frame that can be readily secured to the curtain, is strong and durable in construction and simple in its application.

With the above and other objects in view, that will hereinafter be apparent, my invention consists in the peculiar features of construction and novel arrangement of the parts set out in the following detailed de-

scription, specifically stated in the appended claims and illustrated in the accompanying drawings, in which:

Figure 1 is a front view of a fragment of a curtain with my improved window frame 40 installed therein.

Fig. 2 is a cross section, partly in perspective view, of a portion of my improved curtain window frame.

Fig. 3 is a cross section thereof and illustrates the same as applied to a portion of a curtain back or top and with one edge of a window glass positioned within the said frame.

Figs. 4, 5 and 6 illustrate modified shapes 50 of a curtain window frame embodying my invention.

In the practical development of my improved construction of curtain window frame, I employ two pieces of flexible material of like width, preferably leather or composition fabric.

Each fabric piece 1 has its opposite edges bent inwardly, as at 10 and 11, and at one edge 10, hereinafter termed the binder or stiff edge, the lapped portions are secured 60 together by stitching 2 to form a continuous loop 3 for receiving a stiffening element, a spring metal rod 4.

The two pieces 1, after their binder edges are provided with the stiffening element 4, 65 as stated, are laid flatwise against each other, with their inturned edges abutting and they are secured by a line of stitching 5, thereby producing a flexible frame member whose opposite edges are separated at 70 the outer side to provide for extending over the edges of the opening cut into the top or back of the curtain member 6, to which member the said frame is rigidly secured by a row of stitching 7 that tightly closes 75 the outer edges 11—11 of the two members 1—1 watertight onto the curtain, as is clearly shown in Fig. 3.

By forming the inner edge of each piece 1 with a loop 3 adapted for receiving a spring rod 4, the said inner edge, while having the desired flexibility, is rendered sufficiently rigid to provide for firmly holding the edge of the window glass 8 in place, it being understood that, in practice, the entire inner edge of the framing, shaped to fit the special design of opening made in the curtain, see 80 Figs. 1, 4, 5 and 6, presents a groove 9 into which the edge of the glass window pane is 85 mounted.

By sewing the two pieces 1—1 together, the said pieces or members 1—1 are clenched in the direction of the length of the flexible frame, such central stitching serving to hold the outer edge 11 firmly and flatwise 95 smoothly attached along the entire edge of the opening in the curtain in which the frame is to be applied.

From the foregoing description taken in connection with the drawings, the complete construction, the manner in which my invention may be readily applied to any desired shape of opening made in the curtain and the advantages attained in the practical application thereof, will be readily apparent 100 to those familiar with the manufacture and the use of automobile curtains.

While I have shown the stiffening rods as held in the divided inner edge of the frame by stitching, the said rods may be 110 secured in the loops of the frame in any other desirable manner.

Since the material of the frame may be of the same kind that the curtain is made of or colored to suit the color of the curtain to which it is to be applied, the said frame is not unsightly and further since the frame is practically in a completed condition before it is applied to the curtain and as its opposite edges are shaped as stated, it can be easily secured to the edge of the curtain opening and mounted around the glass edge without the exercise of skill and in very little time.

What I claim is:

- 15 1. A curtain window frame composed of two fabric members of like shape, each of the said members having a metal reinforce in the inner edge thereof, the said members being secured together near their central portions, the reinforced inner edges of the 20 two members forming a groove for the reception of the edges of a glass window pane, the outer edges of the fabric members being adapted forlapping over and stitched to the edge of the opening in the curtain to which 25 the frame is to be applied.
2. A curtain window frame formed of two pieces of fabric material of like widths, the inner edge of each piece having a hem, and a stiffening rod secured within the said hem,

the two pieces being flatwise secured together in the direction of their length, whereby the outer edges are separated and adapted for being stitched over and along the edge of the opening in the curtain to which the frame is to be attached, the said reinforced separated ends of the two pieces constituting a groove extending around the length of the frame and adapted for holding the edges of the window glass.

3. In a curtain window frame, the combination with a glass pane of suitable design and a curtain having an opening of like design; of a frame constructed of fabric composed of two like shaped pieces, each piece having a metal reinforce in the inner edge and the outer edge lapped over onto the body thereof, the two pieces being held with their overlapped portions abutting, stitching that connects the two pieces in the direction of their length and substantially midway the inner and outer edges thereof, the inner or metal rim portions of the pieces forming a groove into which the edges of the glass pane is received, the outer edges of the said pieces being stitched together and to the edge of the opening in the curtain.

FRANK W. MORSE.
